UNITED STATES PATENT OFFICE

2,085,918

A BUILDING

Louis A. Mazzarino, Salt Lake City, Utah

Application April 11, 1933, Serial No. 665,481

1 Claim. (Cl. 72—55)

My invention relates to method of building brick buildings and more particularly to brick roofs and has for its object to provide a building construction which is fire proof, shock and earthquake proof, and which is interlocking and strong in construction.

A further object is to provide a fire proof roof or ceiling for buildings, which may be held by fewer vertical supports and which will use fewer 10 steel girders or beams than is now the practice, with resulting stronger and more substantial roof.

A still further object is to provide a fire proof constructed roof, floor, or ceiling, in which bricks 15 are used between horizontally laid I-beams, with the laying of the bricks so positioned as to result in a self supporting arch with more strength and durability than has heretofore been accomplished.

20 A still further object is to provide a reinforcing for the walls of a building so that the stress of the roof will not force the walls outwardly and to prevent one wall collapsing when shocks occur.

These objects I accomplish with the construction 25 shown in the accompanying drawing in which similar numerals and letters of reference indicate like parts throughout the several views and as described in the specification forming a part of this application and pointed out in the appended 30 claim.

In the drawing in which I have shown the construction of my building

Figure 1 is a vertical section through a portion of the roof.

35 Figure 2 is an inverted plan view of a portion of Figure 1.

Figure 3 is a horizontal section through the side walls, showing the locking means employed.

Figure 4 is a side view of the ends of the cables 40 at one corner of the building showing the vertical locking bars.

The present day construction of roofs or ceilings is made by setting the I-beams fourteen inches apart and laying tile in between each I-beam and 45 with my invention I lay the I-beams at least thirty-six inches apart and lay four nine inch bricks in between the beams as shown in the drawing, the distance between the beams and the length of the bricks may be varied as desired.

50 In the drawing I have shown the roof as A and the sidewalls as B. The roof is laid with the I-beams C, D and E as shown in horizontal position and between each I-beam I then lay bricks as shown in Figure 1, with the brick 1, laid with the end touching and resting against the base of the I-beam C and the flange thereof inclined slightly upwardly therefrom with the brick 2 then laid against the end of the brick 1 but inclined less from the horizontal plane. The brick 3 is laid in

an opposite incline to brick 2 and brick 4 is laid between the end of brick 3 and the I-beam D on the same incline as brick 1. The end of the brick 4 is then wedged between the brick and I-beam D as necessary. The mortar F which is used between the bricks is allowed to stick down between each crack in the bricks to enable the plasterers to lay their plaster tying the plaster to the roof by this mortar. The next row of bricks is then laid starting with a half of a brick 5 at the 10 end, with three whole bricks 6, 7 and 8, laid thereto adjacent the bricks 1, 2, 3 and 4, and another half brick 9 is laid at the end of this flight with this brick resting against the I-beam E.

The entire roof may be thus constructed, but 15 care must be taken to lay about a foot distance between each I-beam before advancing any stretch of bricks between any given set of I-beams more than that distance in order to prevent springing of the I-beams.

20 The tops of the I-beams are then provided with holes 12, therethrough, through which bolts or screws 13 may be passed to secure stringers 14 thereto. Onto the top of the stringers 14 a suitable floor G may then be laid. Before the floor 25 is laid the upper surface of the brick arches between each I-beam is treated or flushed over by a thin coating of fluid cement to insure complete closure of all fissures between each brick and to form a solid roof. Plaster 15 may then 30 be placed on the under surface of the bricks to make the space between each beam flush with the bottom of the beam and a finish coat 16 may be spread thereover to completely finish the ceiling, if desired, or the bare bricks may be left if 35 desired.

Laid in each vertical wall of the building are cables 20, 21, 22, and 23, with the ends of each cable formed into a loop 24, and vertical tie bars 25 are placed through the loops to lock the ends 40 of the cables into the corners interlocking the entire wall structure into a solid unit.

When more floors are desired above the one laid, the I-beams will be laid across the building in a direction at right angles to the first floor 45 or ceiling.

Having thus described my invention I desire to secure by Letters Patent and claim:

In a building the combination of the side walls held in place by longitudinal cables extending 50 from corner to corner and crossing over each other at the corner; loops in the end of each cable; vertical tie rods at each corner setting the ends of each cable to a tie-rod; I-beams set across the top of said walls; and arches formed between 55 each I-beam formed of bricks built therein end to end set against the bottom flange of the I-beams.

LOUIS A. MAZZARINO.
